GLASS DOOR LOCKING BAR

James E. Malone, 11071 Denton Road,
Dallas, Tex. 75229

Filed Jan. 2, 1968, Ser. No. 10,028

Term of patent 14 years

Int. Cl. D8—03

U.S. Cl. D8—203

FIG. 1

FIG. 2

FIG. 3

FIG. 4

FIG. 1 is a perspective view of a glass door locking bar, the broken lines used to show the environmental use only;

FIGURE 2 is a perspective view of the glass door locking bar employing the design of invention;

FIGURE 3 is a fragmentary bottom view of the device of FIGURE 2 shown partially broken away for convenience of illustration;

FIG. 4 is a fragmentary detail view of the configuration of the end of the device of FIGURE 2 nearest its point of installation in a door jamb such as that seen in FIGURE 1.

I claim:

The ornamental design for a glass door locking bar, as shown and described.
